Atty.

UNITED STATES PATENT OFFICE.

CHARLES A. JOHNSON, OF MOLINE, ILLINOIS.

PLOW.

SPECIFICATION forming part of Letters Patent No. 514,552, dated February 13, 1894.

Application filed July 11, 1893. Serial No. 480,181. (No model.)

To all whom it may concern:

Be it known that I, CHARLES A. JOHNSON, a citizen of the United States, residing at Moline, in the county of Rock Island and State 5 of Illinois, have invented a new and useful Attachment to Ground-Plows, of which the following is such a full, clear, and exact description as will enable others to make and use the same.

My attachment is designed to be affixed to that part of a ground plow known as the land-side, and its object is to provide a wearing surface, which shall protect the land side from the friction of the earth, and, at the same 15 time, furnish means to regulate the depth to which the plow shall run.

In the drawings accompanying and forming part of this specification, wherein the same character of reference refers to the same part 20 in the several views, Figure 1, is a side elevation of a plow equipped with my attachment, showing its manner of attachment to the land-side. Fig. 2, is a cross section of Fig. 1 on the line $x-y$. Fig. 3, is a plan of the attachment. 25 Fig. 4, is a cross section corresponding to Fig. 2 showing a modified form of my attachment; and Fig. 5, is a plan of said modified form.

The said attachment consists of the plate B, of steel or other suitable material which fits 30 upon the land-side A, of the plow, as shown in Fig. 1. The plate B is triangular in its general outline, and its apex or point is in front on a level with the lower edge of the land-side. The upper edge of the plate slants upward and backward, is drawn out thin, and fits the land-side closely so as to minimize the friction of the earth. The outer, bearing surface of the plate is polished so that the earth will scour off from it readily. The plate B is 35 adjusted near the rear extremity of the land-side and is provided with a vertical slot c, through which passes the set-bolt C, which holds the attachment in position. The attachment should extend at least as far backward as the rear extremity of the land-side. 40 The plate B is provided with the shoulder b, which projects beneath the land-side when the attachment is in position, and forms a foot or shoe for bearing upon the earth beneath. 45 By means of the set-bolt C and the slot c the

attachment may be so adjusted as to bring the shoulder b in contact with the lower edge of the land-side, or at any desired distance below it, within the limits imposed by the length of the slot c.

55

When the attachment is so adjusted as to bring the shoulder below the lower edge of the land-side by any distance, the effect is to elevate the rear of the plow and depress the point, and cause it thereby to run deeper into the 60 earth. In this manner it is possible to regulate the depth at which the plow is to run by means of this attachment. At the same time, the attachment is taking upon its bearing surface the friction and wear that would otherwise come upon those portions of the land-side which it overlies and covers, and so protects and preserves the plow.

65 Figs. 4 and 5, show a modified form of the attachment. The wing b' extends outward 70 from the plate B in the direction of the un-plowed land, and cuts under the surface so as to enable the plow following to turn a slightly wider furrow. The wing b' should be slightly above the level of the lower edge 75 of the foot b.

The vertical adjustment of the plate B, which is secured by the means set forth, might be accomplished in other ways than by means of the slot in the plate, e. g. by means of a 80 slot in the land-side, or by a row of bolt holes in either plate or land-side or both, without departing from the spirit of this invention.

I am aware that prior to my invention plows have been constructed with vertically adjustable heels, and land sides, and also with vertically adjustable wear plates upon the land-sides. I do not claim such device, broadly, for that reason; but I am not aware that such wear plates have been so constructed as to 85 enable them to be attached to any of the ordinary ground-plows now in use without a specially constructed landside for their attachment, or that they have ever, prior to my invention, been of the shape, thinness, and 90 adaptability of my attachment herein described, or that they have been attached with a single bolt and without other attachment by bolt, pivot, hook, or other device whatever.

95 Having thus described my invention, what 100

I claim as new, and desire to secure by Letters Patent, is—

1. The attachment to a ground plow described, consisting of the triangular plate B, vertically adjustable upon the landside of the plow, and secured thereto by a single bolt, said plate bearing a foot projecting beneath the landside and forming a heel thereto; said plate also bearing a wing b' on the opposite side thereof, as and for the purpose set forth.

2. The combination with the landside of a ground plow, of a triangular wear plate vertically adjustable, attached thereto, bearing a foot projecting beneath said landside, and a horizontal cutting wing b' on the opposite side thereof, as set forth.

CHARLES A. JOHNSON.
